UNITED STATES PATENT OFFICE.

GEORGE J. KLINDT, OF BURLINGTON, IOWA.

CLOSET-FLANGE.

1,149,269.

Specification of Letters Patent. Patented Aug. 10, 1915.

Application filed December 20, 1913. Serial No. 807,955.

To all whom it may concern:

Be it known that I, GEORGE J. KLINDT, a citizen of the United States, residing at Burlington, in the county of Des Moines and State of Iowa, have invented new and useful Improvements in Closet-Flanges, of which the following is a specification.

The invention relates to an improved closet flange and hub combination for the proper connection and for use as a fitting between the soil pipe and the closet bowl, the construction providing a simple type of connection which will be absolutely proof against leaking, and securing mechanically as well as permanently sealed gas and water tight joint between all the parts thereto.

The main object of the present invention is the provision of a removable seat ring for coöperation with the flange proper and closet bowl gasket and capable of being adjusted to insure and maintain the necessary coöperation with the flange and hub combination to prevent leakage, said flange and hub combination so constructed as to permit of the flange being leveled on the floor and securely screwed in place.

The invention in the preferred form of details will be described in the following specification, reference being had particularly to the accompanying drawings, in which:—

Figure 1 is a view in section, partly in elevation, illustrating the application of the improved closet flange, and hub combination with removable ring seat and adjusting ring between the hub and soil pipe. Fig. 2 is a perspective view of the flange proper, showing one method of locking the ring seat to the flange by lugs. Fig. 3 is a perspective view of the seat ring, showing it with lugs for interlocking with the flange on the hub.

The improved connection comprises a hub proper including a ring shaped hub element 1 having a lateral flange 2, the latter constituting the floor flange, formed with a series of screw receiving openings 3, whereby the connection may be secured to the floor, after being properly leveled. The flange 2 is formed with a series of bolt receiving slots 4 to receive the bolts 5, by which the flange 6 of the bowl 7 is secured. The slots 4 are enlarged at one end to permit passage therethrough of the head of the bolt, the opposing side walls of the slot beyond the enlarged portion being upwardly convergent as at 8. The heads 9 of the bolt are rec-

tangular in outline with their side edges upwardly convergent so that these heads may be introduced into the enlarged portions of the slots and moved longitudinally fitting 60 convergent side walls of the slots, as will be evident from the drawings. This arrangement permits adjustment of the bolt to the proper position independent of the fixed position of the flange proper, which is 65 leveled independent of the soil pipe connection.

The hub element 1 of the flange proper is formed at its lower edge with an inwardly projecting rib 10 to receive the soil pipe, the 70 space above the rib between the inner surface of the hub element 1 and the soil pipe being reserved for the usual packing.

The hub member 1 in proximate alignment with the lower edge of the flange 2 is 75 cut away to form an annular ledge 11 and above the ledge the wall is formed with locking recesses 12 having entrance openings 13 formed by cutting away the material forming the upper wall of the locking 80 recesses.

A seat ring 14 comprises an annular member of a size to overlie and bear upon the ledge 11, the outer edge of the member being provided with lugs 15 adapted to engage the locking recesses, the lugs passing through the openings 13 to a position on the ledge 11, from which they are turned into the recesses 12. The upper edges of the lugs are slightly inclined to induce wedging action, as they are turned into the recesses and in the preferred form a packing ring 16 of suitable form is interposed between the bottom of the seat ring and ledge 11 so that when said ring is turned into locking position the 95 sealing ring is compressed to insure air-tight juncture at this point. The upper surface of the seat ring is slightly concave and inwardly inclined, that is in transverse section, this depression forming a seat 17 for a 100 rounded packing ring 18 on which the appropriate flange of the bowl rests and which is put under compression as the closet bowl is drawn to its place, thus sealing this juncture, as will be obvious, the ring can be reversed using a flat surface as in the screwed and snap ring types for a flat gasket.

The inner edge of the seat ring is formed with diametrically opposed depressions 19 to receive the edges of the operating bar 20, 110 by means of which the seat ring may be forced to such position that it will insure a

sufficient pressure upon the packing to maintain an absolutely gas-tight position. When the ring is in a reverse position to that shown in the drawings, the lugs 15 5 completely fill the entrance openings 13 for preventing turning movement of the ring. The invention presents a combination that permits of said parts being set level in the floor even though the soil pipe is not plumb 10 or at perfect right angles with the floor level. The adjustable feature insures a level setting of the closet bowl. The inner protecting ring 10 on the lower end of the hub 1 makes a closed circular member around 15 the soil pipe to retain the packing and lead corking to form a permanent joint. The removable seat permits the ready accessibility 20 of packing and corking tools. The hub may be constructed to permit the use of the threaded soil pipe for forming a threaded instead of the cork joint or may with equal 25 facility permit a wiped joint with the soil pipe.

The invention is primarily intended to 25 permit of the adjustable connection between the closet bowl and soil pipe forming a durable gas and water tight joint, while at the same time permitting ready assembling disconnection, or renewal of parts, as may 30 be necessary.

What is claimed is:—

1. A closet flange hub combination including a flange proper; bolt receiving openings formed in said flange proper, and a reversible seat ring adapted to be removable 35

and interlocking with the flange proper by lugs, said ring having a flat under surface and a concave upper surface, said ring being reversible to present a concave or a flat packing engaging surface. 40

2. A closet flange including a flange proper, bolt receiving openings formed in said flange proper, and a reversible seat ring adapted to be removable and interlocking with the flange proper, said ring being removable, the upper surface of the ring being downwardly and inwardly curved 45 while the under surface is flat so that the ring can be reversed to present a concave or flat surface to a flat ring gasket. 50

3. A flange including a ring member formed to provide an inner shoulder, interlocking recesses formed in said member above the shoulder, and a reversible seat ring having ribs to interlock in said recesses. 55

4. A flange including a ring member formed to provide an inner shoulder, interlocking recesses formed in said member above the shoulder, a reversible seat ring having ribs to interlock in said recesses, and 60 a gasket interposed between said ring and shoulder and compressed in the interlocking movement of said ring.

In testimony whereof I affix my signature in presence of two witnesses.

GEORGE J. KLINDT.
